UNITED STATES PATENT OFFICE.

JACOB J. LIBBY, OF FOSTORIA, OHIO.

GRAIN DOOR.

Application filed February 4, 1921. Serial No. 442,408.

To all whom it may concern:

Be it known that I, JACOB J. LIBBY, a citizen of the United States of America, residing at Fostoria, Seneca County, Ohio, have 5 invented new and useful Grain Doors, of which the following is a specification.

This invention relates to closures of a readily removable type, for bin openings or doorways.

10 This invention has utility when incorporated as a grain door for box cars of railroads.

Referring to the drawings:

Fig. 1 is a side elevation of a railway box 15 car having an embodiment of the invention incorporated therewith;

Fig. 2 is a plan view of an assembled sectional unit;

Fig. 3 is a perspective view of the cleat 20 carrying side of one of the sections of the unit;

Fig. 4 is a perspective view of the other section of the unit from that shown in Fig. 3; and

25 Fig. 5 is a fragmentary view on an enlarged scale showing in plan the hook and seat engagement, as well as the button holding assembly features.

A railway box car 1 is shown as having a 30 side door 2 slidably clear of the doorway or opening 3 having parallel sides 4.

A door section 5 is shown as having a cross cleat 6 slightly spaced from an end 7 of the section 5. Prongs or points 8 may incline away from the section 5 and the cleat 6 toward this free end 7 of this section 5. The remote or inner end of this section 5 is provided with a pair of projections or hooks 9 to detachably engage with seats 10 in 40 plates 11 anchored by rivets 12 to the inner face 13 of a second door section 14. This second section 14 has a cleat 15 on its outer side, similar to the cleat 6 of the section 5, with door frame engaging points or prongs 45 8, also protruding therefrom, similar to the prongs 8 of the cleat 6. The two rows of seats 10 extend inward from the cleat 15, but upon the opposite side of the section 14. Beyond these seats 10 and still more remote 50 from the cleat 15, this door section 14 has a pair of parallel slots 16.

The first door section 5, is shown as having a pair of pins 17 fast therewith, provided with swiveled cross-bars or buttons 18, which 55 in protruding after insertion through the slots 16, may be turned crosswise of such

slots 16, and thereby readily serve as holding means for maintaining the two sections of the door unit in assembled parallel relation. The hooks 9 as engaged in different seats 10 60 provide a ready assembly means for varying the effective length of the unit to meet conditions of varying widths of doorways.

In practice, when a car is cleaned out and ready to be loaded with grain, or other bulk material, a pair of unit sections are taken, the hooks 9 being entered in seats 10 in such region that as the slightly buckled sections are forced into parallel relation with the projections of the sections 5, 14, beyond the 70 cleats 6, 15, resting against the inner side of the door frame or sides 4, the cleats 6, 15, may be shifted toward said sides 4 and the points 8 embedded therewith. The slots 16 permit the buttons 18 to move therethrough 75 to the outer side of this assembled door unit at the final parallel position, and whatever be the width adjustment, these button holding means may be turned for locking the door unit. With small or very fine bulk material, gunny sacking or other backing may be placed along the door frame, the threshold and between the units as built up, to such height as may be desired in closing the doorway. However in top groove 19 a rope 20 80 85 may be partially embedded to project and seat in bottom groove 21 of the next section to pack the joint. When the loaded car reaches its destination and it is desired to unload the same by allowing the material to 90 flow from the door, there is no occasion to mutilate the car or the door units. In fact, the most ready way is to turn the buttons 18 to align with the slots 16, and then with little effort the section 14 may be swung outward at an easily controlled rate for governing the discharge stream, as the first section is also drawn outward by the hooks 9 still engaging the seats 10. This outward opening of the door unit, automatically withdraws the points 8 from embedded relation.

Assuming that this is the lower door unit which has been removed, the flowing of the bulk material in discharge does not result in a toppling down of the upper sections, 105 for the embedded points 8 hold them in position, and as the material is clear of these sections, they may be removed as desired for convenient access to the car in working the material from the ends of the car toward 110 the doorway and out.

There is accordingly provided a structure

which when built of wood and faced or armored with metal, may be substantial and durable for repeated and long continued use as a tight closure for car doors in the transporting of fine bulk materials.

What is claimed and it is desired to secure by Letters Patent is:

1. The combination with a car provided with an opening having parallel sides, of a closure for the opening embodying two sections, and adjustable connecting means hinging the sections together to approximate the width of the opening between the parallel sides thereof, when the sections are in parallel relation, there being a lock for said connecting means which in the adjustment of the sections is shiftable as to only one of the closure sections.

2. A grain door unit for railway box cars embodying a pair of sections, each of less length than the width of the car doorway, and a hinge connection between the sections adjustably and detachably uniting the sections, there being a lock for said connection mounted on one of the sections independently of shifting therealong.

3. A door section having a projection, a second door section having a series of seats engageable by the projection in adjusting the assembly of the sections to different widths of doorways, said sections being provided with embedding means for engaging opposite sides of a door frame, and means adjustable along one of said sections only for drawing the sections in position against disengagement of the projection from a seat and simultaneously mounting the sections in the frame by driving the engaging means into the frame.

4. A door section having a terminal projection, a second door section having a row of seats which in set up position of the sec-

tion extend transversely of a doorway, said sections being provided with embedding means for engaging opposite sides of a door frame, and means carried by the projection carrying section adjustable along one of said sections only for drawing the sections assembled in parallel relation with the projection engaging a seat and simultaneously 45 mounting the sections in the frame by driving the engaging means into the frame.

5. A sectional grain car door unit embodying a pair of hinge connected sections having their remote ends provided with cross cleats 55 spaced inwardly from such ends, and doorway frame engaging prongs carried by said sections adjacent said cleats, said pair of sections being adjustable for width, and a lock for the hinge fixed as to one of said 60 sections.

6. A grain car door unit embodying a pair of sections for assembly with each other and each provided with a cross cleat spaced from the outer end thereof, the other end of 65 one of said sections being provided with a pair of hooks, the other section being provided with two rows of seats extending away from its cleat and engageable by the hooks in assembling the sections into parallel relation to have the cleats approximate a doorway width and the projections beyond the cleats engage a doorframe on the inner side, said seat carrying section having more remote from its cleat than said seats, a pair 70 of slots, and buttons carried by the hook carrying section to protrude through said slots and shiftable to lock the sections in parallel relation, and releasable from outside the door for outward swinging of the door in 75 door unit removal.

In witness whereof I affix my signature.

JACOB J. LIBBY.
